UNITED STATES PATENT OFFICE.

TIMOTHY ROGERS, OF SPRINGFIELD, OHIO, ASSIGNOR TO THE ROGERS FENCE COMPANY, OF SAME PLACE.

IRON FENCE.

SPECIFICATION forming part of Letters Patent No. 292,859, dated February 5, 1884.

Application filed March 24, 1883. (No model.)

To all whom it may concern:

Be it known that I, TIMOTHY ROGERS, a citizen of the United States, residing at Springfield, in the county of Clarke and State of Ohio, have invented certain new and useful Improvements in Iron Fences; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in iron fences, to iron fences having double parallel rails, and to that class of iron fences in which the picket ornaments are rigidly attached to the rails and are adjusted therewith independently of the picket-rod.

The object of my invention is to strengthen the opening in the ornament through which the picket-rod extends; also, to strengthen the fastening parts of the same, and to construct the ornament so as to allow the fence to front toward either side.

Figure 1 is a perspective view of the ornament and a portion of the rails and picket-rod of my improved iron fence. Fig. 2 is a side elevation of the same. Fig. 3 is an end view 30 of the parts seen in Fig. 2 from the left.

The rails best adapted to my improved fence are square in their cross-section, and are placed in the same horizontal plane, with their angles inward, and the picket-rod of the same 35 form inserted between them. The ornament is in two sections, one above and the other below the rails. The ornament shown consists simply of single plane curved frame-bars extending upward and downward from their 40 engaging ends, so as to form in general outline an irregular ring of hexagonal form, the extreme side of which is in the shape of a segment, *e*, with an oblong opening, *a'*, therein, extending vertically through it. This slot or 45 opening extends the full length of the segments, its ends conforming in shape to the angles of the picket-rod. Through this slot in each section the vertical picket-rod *a* extends. The ends of the ornament frame-bars are made 50 triangular in their cross-section, and extend outward in opposite directions, fitting exactly

into the triangular space formed between the contiguous surfaces of the rails and the inside of the upper and lower bars of the clip-band *c*, which is made to fit over the square rails *b* accurately. In putting the members of the fence together, the sections of the ornaments are put in place with their ends *d* exactly opposite each other upon the upper and under surfaces of the rails, and the clip-band *c* forced 55 on over the rails and the ends *d* of the ornament, upon one side thereof. The picket-rod *a* is then inserted between the rails down through the oblong slots or openings *a'* in upper and lower ornament-section. The clip-band is then driven over the rails and ends *d* of the ornament upon the opposite side, and thus the picket is secured in place.

It will be noticed that in this form of fence either picket or ornament can be easily removed, if necessary, for repairs. The connection formed by the ends of the ornament with the rails and the bands, securing them together, makes it very strong; yet the removal of either picket or ornament can be easily effected by driving the band *c* from off the ends *d* of the ornament. The degree of adjustment is shown by the double arrow *f*, Fig. 2.

I claim as my invention—

1. The combination, with the double or parallel rails lying in the same horizontal plane, of the ornament having the ends of its sections adapted to engage with the inner surfaces of said rails, and the transverse clip-band adapted to slip over the ends of said sections and secure the whole together.

2. In an iron fence having double rails, an ornament having a vertical longitudinal opening or slot in each of its two opposite arch-bars, said slot or opening being for the purpose of 90 allowing the picket-rod to extend therethrough and to admit of the adjustment of the ornament and rails without disturbing the relative position of the picket-rod.

3. In a double-rail iron fence, an ornament in two opposite sections, having its ends shaped to conform to the space between the rails upon either side of the same, and confined therein by an encircling band, as hereinbefore set forth.

4. The combination, with the double parallel rails and the picket, of the ornament and the clip-band, the former having the vertical

oblong slot through the middle of its bars extending in the central longitudinal line of the fence, whereby said ornament is adapted for the insertion of the picket, and the necessary adjustment of said rails and ornament to the latter allowed, as set forth.

5. The combination, with the square parallel rails *b*, the intermediate picket, *a*, and the band *c*, of the ornament-sections Δ , having the angular ends *d*, said ornament-sections being

vertically slotted to admit the picket and permit of the adjustment of the rails and ornament thereto, as specified.

In testimony whereof I affix my signature in presence of two witnesses.

TIMOTHY ROGERS.
